UNITED STATES PATENT OFFICE.

CHARLES E. TITCHENER, OF BINGHAMTON, NEW YORK.

DESIGN FOR AN AUTOMOBILE OR CARRIAGE BOW-SEPARATOR.

45,132.

Specification for Design.

Patented Jan. 6, 1914.

Application filed October 2, 1913. Serial No. 793,074. Term of patent 7 years.

● *To all whom it may concern:*

Be it known that I, CHARLES E. TITCHENER, a citizen of the United States, residing at Binghamton, in the county of Broome and State of New York, have invented a new, original, and ornamental Design for Automobile or Carriage Bow-Separators, set forth in the annexed specification, reference being had to the accompanying drawing, forming part thereof.

In the drawings Figure 1 is a side eleva-

tion of the bow separator; Fig. 2, an end elevation thereof; Fig. 3, a bottom view; and Fig. 4, a plan view.

I claim:

The ornamental design for an automobile or carriage bow separator, as shown.

CHARLES E. TITCHENER.
